DIFFUSION CLOUD CHAMBER

Robert E. Fearon, Tulsa, Okla., assignor to Electro Chemical Laboratories Corporation, Tulsa, Okla., a corporation of Delaware

Filed Mar. 28, 1958, Ser. No. 724,743

12 Claims. (Cl. 250—83)

The present invention relates to apparatus for demonstrating visually the tracks of ionized particles and more particularly to diffusion cloud chambers.

Droplet precipitating cloud chambers, starting with the so-called "Cloud apparatus" of C. T. R. Wilson, operate on the same general principle, namely, that a supersaturated vapor will condense into liquid drops preferentially at places where there are charged particles, such as charged atoms or molecules. The charged particles act as centers or nuclei for the drops which are formed. Electrically charged atoms or molecules are produced in profusion, in pairs of equal numbers of positive and negative particles along the path of any ionizing particle, such as a rapidly moving free electron, any alpha particle, any charged meson, any high speed proton or deuteron, any fission particle, or any recoiling nucleus set in motion by being hit by a neutron. These are examples of the many circumstances under which tracks will appear in a supersaturated atmosphere. Such tracks are especially instructive, for the reason that, under suitable conditions practically every charged atom or molecule becomes the location of a drop very quickly after it is generated, and a count of the drops under good magnification will determine how many ion-pairs there were in the track, or in the portion of it which is observed. From this, some very fundamental things may be learned, such as, for example, how many electron volts of particle energy were released in the observed portion of the track. Also, in view of the fact that the density of the droplets is expected to increase as the ionizing particle slows down (in terms of the number of drops per unit path length) it is often possible to look at a track and tell which way the particle moved in passing over the trajectory it followed in producing the track, i.e., the sense of direction of the motion of the primary particle along the track.

As a practical matter, charged atoms and molecules are not the only points in space where a droplet can be initiated in a supersaturated atmosphere. Dust particles, and even peculiar molecules of certain offensive contaminating substances can "fool" the vapor molecules and produce false centers of droplet formation, not corresponding in any way with nuclear radiation. In general, unless there is a continuous source of some offending "cloud seeding" material, the particles and molecules of this sort shortly become exhausted by being carried down with the droplets they acquire, and are thus swept out of the gas and vapor filled space. In many of the larger cloud chambers, such purging takes quite a long time. For various reasons, smallness of structure favors quick purging.

Another practical matter in the design and operation of a cloud chamber is supersaturation, and the degree thereof. Too much supersaturation produces completely nonselective droplet formation, and makes droplets everywhere all the time, in complete disregard of nuclear tracks. In the expansion chamber of C. T. R. Wilson, this was arranged by careful choice of the initial tempera-

2

ture, and control of the degree of expansion (adiabatic) of the originally 100% water vapor saturated space.

In the case of a diffusion cloud chamber the control of the degree of supersaturation is accomplished by choice of temperature of the vapor source, the gradient of temperature, in terms of the number of degrees per unit distance downward in the region of vertical gradation of temperature, and the rate of diffusion of the vapor in question in whatever gas is chosen for the atmosphere.

10 An insufficient rate of supply of vapor, or an insufficient vertical gradient of temperature, results in too small a degree of supersaturation. The evidence of this condition is failure of the droplets to form at all on the tracks, which are not effective for nucleation unless the excess of vapor pressure above equilibrium is sufficient. With too much supersaturation, too many tracks appear and they will, in general, have no relevancy to nuclear radiation.

20 The conventional cloud chambers commercially available are generally of large size so that the walls will be remote from the major portion of the active volume of the chamber. Thus relief of supersaturation in any zone by diffusion of vapor molecules to the walls and condensation thereon are not a major problem in the operation of such a device. Also in large size cloud chambers of conventional design, the supply of vapor, e.g., methanol, may be controlled by separate devices such as a variable heat source for the methanol. Also, in the commercial models of large size, there is but little trouble maintaining exactly and in an orderly manner the desired vertical gradient of temperature in the system, for the reason that the disturbing effect of the walls, temperature-wise, is remote. Such commercial models of cloud chambers also provide temperature regulation systems to maintain their cold sources at constant, determined low temperatures.

30 The principal object of the invention has been the provision of a novel and improved diffusion cloud chamber.

40 More particularly, it is an object of the inventor to provide a novel and improved diffusion cloud chamber of miniature size.

45 A further object of the invention has been the provision of a novel and improved diffusion cloud chamber of miniature size which is simple and economical in construction.

50 Another object of the invention has been the provision of a novel and improved diffusion cloud chamber which provides high sensitivity even for low energy radiation, such as that of about 200 electron volts.

55 Still another object of the invention has been the provision of a novel and improved diffusion cloud chamber having a low recovery time after radiation overload.

55 A further object of the invention has been the provision of a novel and improved diffusion cloud chamber of simple and economical construction which affords good reproducible performance.

60 A feature of the invention has been the provision of a novel and improved diffusion cloud chamber having magnification of the sensitive zone, a strong continuous lighting which does not appreciably affect the temperature, and a cavity arrangement for dark background in viewing.

65 Another feature of the invention has been the provision of a novel and improved diffusion cloud chamber which has no troughs which occlude any portion of the field of view.

70 Still another feature of the invention has been the provision of a novel and improved diffusion cloud chamber in which vapor is supplied from absorbent material situated on the sidewalls of the optical tube.

70 Another feature of the invention has been the pro-

vision of a novel and improved diffusion cloud chamber in which dewfall on the eyepiece is avoided.

Other and further objects, features and advantages of the invention will appear more fully from the following description of a preferred embodiment of the invention which is illustrated in the drawing.

The drawing is a longitudinal sectional view of a preferred diffusion cloud chamber in accordance with the invention.

Referring now to the drawing, the diffusion cloud chamber of the invention comprises a cold reservoir 10, a cold transfer assembly 11, a Dewar vacuum flask 12 and an eyepiece and viewer assembly 13. As has been explained previously, there are many factors which can adversely affect the operation of a cloud chamber. The design of the illustrated form of the invention, both with respect to shape and size of parts, represents what is believed to be an optimum combination. So far as is presently known, the size and shape of the various parts, particularly the cloud chamber space and viewer assembly, are critical for securing best results. For this reason, the drawing illustrates the cloud chamber of the invention substantially in accurate full scale.

The cold reservoir 10 is illustrated as an open-necked insulating bottle 14 having a hollow chamber 15 adapted to be filled with a freezing mixture. The bottle 14 is preferably of the Dewar flask type and may be a commercially available thermos bottle. For convenience the internal structure of the bottle 14 has not been illustrated. In one form of the invention, the bottle 14 was an Aladdin one pint thermos bottle. The charge in the chamber 15 should be one which will produce a temperature of -50° F. or lower. A variety of freezing mixtures are suitable for this purpose, for example, white gasoline stirred with small lumps of Dry Ice. A desirable freezing mixture, because of its odorless and non-toxic characteristics, is Freon liquefied among lumps of Dry Ice.

The cold transfer assembly 11 comprises a cold transfer rod 16, a hollow cylindrical stopper 17 and a washer 18. The stopper 17 has a side wall 19 shaped to fit within and close the open neck of the bottle 14 and a bottom wall 20 having a central hole adapted to accommodate central cylindrical portion 21 of the rod 16. The rod 16 has a peripheral groove 22 which is engaged by the rim of the hole in the bottom wall 20 thereby to retain the rod 16 and stopper 17 in the relative positions illustrated.

The end of the rod 16 within the chamber 15 is tapered, as shown at 23, making an angle of about 20° with the horizontal. The central portion 21 of the rod 16 terminates at a shoulder 24, the remainder of the rod 16 having a larger diameter, as shown at 25. The end 25 of the rod 16 is provided with a bore forming a chamber 26 which may be about 1 inch in diameter and about 1.125 inches in length, exclusive of the tapered end 27. A cylinder 28 of thin black material is provided in the chamber 26. A disc 29 of similar material is provided in the inside end of the chamber 26. The cylinder 28 and disc 29, which may be made from a single thickness of black art paper, form a lining for the chamber 26.

The rod 16 should be made from a highly heat conductive material such as aluminum. The stopper 17 may be made from rubber or a low temperature resistant plastic.

The washer 18, which may conveniently be made from cork, rubber or a low temperature resistant plastic, fits tightly between the bottom 20 of the stopper 17 and the shoulder 24, the washer being in intimate contact with the adjacent wall of the rod 16. The diameter of the washer 18 is slightly greater than the diameter of the end portion 25 of the rod 16. The bottom 20 of the stopper 17 may be provided with a small hole, if desired.

The Dewar flask 12 is open at both ends so as to

form a hollow cylinder. The walls of the Dewar flask should be made from a temperature change resistant glass such as Pyrex glass. The outer wall 30 might be, for example, 55 mm. thick while the inner wall 31 might be 38 mm. thick, the space between being evacuated through a sealed-off opening 32. One end 33 of Dewar flask 12 fits between the outer surface of the washer 18 and the inner surface of the stopper 17. A sealing contact is afforded between the wall 31 and the washer 18.

10 The eyepiece and viewer assembly 13 comprise a bushing 34, a hollow cylinder 35 and a glass lens 36 forming an eyepiece.

The bushing 34 fits within end 37 of the Dewar flask 12 and is cemented thereto for retaining the bushing in the end of the flask 12 and for providing an air-tight fit. An outwardly extending flange 38 on the bushing 34 contacts the end of the flask 12. The bushing 34, which may be made of aluminum, is provided with internal threads which are in threaded engagement with external threads provided on cylinder 35, which may likewise be made of aluminum. End 39 of cylinder 35 communicates with a chamber 40 which in turn communicates with chamber 26. Rotation of the cylinder 35 changes the axial position of the cylinder 35 with respect to the bushing 34. Bushing 34 may, if desired, be made in the form of a resilient washer, such as cork, fitting tightly in the end of the flask 12 and permitting sliding motion of the cylinder 35. In such case threads would not be provided on the cylinder 35.

30 Lens 36 is cemented in place in a shoulder 41 provided in the outer end of the cylinder 35. The cylinder 35 is provided with a threaded hole adapted to receive a removable screw 42. The inner surface of the cylinder 35 is provided with a lining 43 of absorbent material such as several layers of filter paper. The lining 43 may be held in place against relative axial movement by a circular spring 44 acting in a groove provided in the inner wall of the cylinder 35. In the embodiment of the invention illustrated, the internal diameter of the cylinder 35 is .875 inch while the axial length thereof is 2.375 inches.

To put the cloud chamber into operation, the subassembly formed by the elements 11, 12 and 13 is removed from the cold reservoir 10 and the chamber 15 of the latter is filled with the freezing mixture, e.g. 45 Freon and Dry Ice. The subassembly is then reinserted into the position shown. With a freezing mixture as described, the stopper 17 should be disposed at a point at which carbon dioxide gas evaporated within the chamber 15 is allowed to escape.

50 The filter paper 43 is wet with the supersaturating vapor source, preferably methanol, either by removing the screw 42 and dropping the liquid on the paper or by removing the cylinder 35 from the bushing 34, wetting the paper, and reinserting the cylinder 35. The 55 space within the cylinder 35, the chamber 40 and the chamber 26 are filled with vapor evaporated from the filter paper 43. The temperature within the chamber 40 will decrease to the desired value for vapor condensation by heat conduction through the rod 16, this temperature being somewhat above the temperature of the freezing mixture. Actually a substantial temperature gradient will exist within the chamber 40 because one side thereof is exposed to the cooling effect of the rod 16 while the other side is exposed to the warming effect 60 of the room temperatures. The atmosphere within the chamber 40 will be supersaturated with methanol vapor. Vapors other than methanol can be used, of course, but they preferably have comparable volatilities, for example, mixtures of methyl and ethyl alcohol and water.

70 Within the region of supersaturation, i.e., within the chamber 40, tracks will be produced whenever a charged particle passes through. By passing a strong beam of light laterally through the chamber 40, as shown by the dotted arrow 45, these tracks are made visible and can

be viewed, either directly or by photographic methods, through the eyepiece 13. Proper focus for the lens 36 can be secured through rotating the cylinder 35. Motion picture records of the cloud trails have proven very instructive.

Cloud chamber operation can be improved by providing an electric field across the chamber 40, for example, by connecting the rod 16 and the bushing 34 to a source of high A.C. or D.C. voltage, e.g., 1000 volts.

While the cloud chamber can be operated with atmospheric air in the chamber 40, in many cases it will be desirable to replace the air with some other atmosphere. This may be done by inserting a tube in place of the screw 42, pumping out the air and refilling with the desired atmosphere. Track length may be increased by filling with low density gases or decreased by filling with higher density gases.

As illustrated, the emergent portion of the eyepiece holder (cylinder 35) is exposed to ambient temperature and it is this temperature which effectively controls the delivery of methanol vapor from the filter paper 43. The delivery of methanol vapor may be limited by surrounding the emergent portion of the cylinder 35 with a thermally insulating wrapper. On the other hand, such delivery may be increased by subjecting the emergent portion of the cylinder 35 to a heat source, such as an incandescent bulb.

Condensed methanol may be removed either by removing the eyepiece holder or the screw 42 and inverting the subassembly of elements 11, 12 and 13.

While the invention has been described in connection with a specific embodiment thereof, various modifications will occur to those skilled in the art without departing from the spirit and scope of the invention as set forth in the appended claims. However, as explained previously, it is believed that the best performance will be obtained with a cloud chamber constructed and proportioned as illustrated.

What is claimed is:

1. A diffusion cloud chamber, comprising a hollow heat insulating member open at both ends, a cold reservoir, a heat conductive member having one end thereof extending into said cold reservoir and having the other end thereof extending into one end of said heat insulating member, mounting means for supporting said heat conductive member in said one end of said heat insulating member, viewing means mounted in the other end of said heat insulating member, and having an emergent portion disposed outside said heat insulating member, the adjacent ends of said heat conductive member and said viewing means being spaced within said heat insulating member to define a chamber, and a source of a volatile liquid in communication with said chamber, said heat insulating member being constructed so that said chamber may be illuminated externally whereby cloud trails created when ionizing particles pass through said chamber may be viewed through said viewing means.

2. A diffusion cloud chamber, comprising a hollow generally cylindrical heat insulating member open at both ends, a cold reservoir, a heat conductive member having one end thereof extending into said cold reservoir and having the other end thereof extending into one end of said heat insulating member, mounting means for supporting said heat conductive member in said one end of said heat insulating member and for supporting said one end of said heat insulating member in said cold reservoir, viewing means comprising a highly heat conducting cylindrical tube having one end thereof mounted in the other end of said heat insulating member and having an emergent end disposed outside said heat insulating member, the adjacent ends of said heat conductive member and said viewing means being spaced within said heat insulating member to define a chamber, and a source of a volatile liquid in communication with said chamber, said source being located within said tube and

being in heat transfer relation with ambient air outside of said heat insulating member for evaporating said volatile liquid to provide supersaturated vapor in said chamber, said heat insulating member being constructed so that said chamber may be illuminated externally whereby cloud trails created when ionizing particles pass through said supersaturated vapor in said chamber may be viewed through said viewing means.

3. A diffusion cloud chamber, comprising a cylindrical Dewar flask open at both ends, an insulated container open at one end and adapted to contain a freezing mixture, a metallic heat conductive rod, mounting means for supporting said rod at an intermediate portion thereof in one end of said Dewar flask, stopper means for closing said open end of said container and for supporting said one end of said Dewar flask in said open end of said container whereby one end of said rod extends into said container, the other end of said rod extending into the interior of said Dewar flask, a hollow cylinder open at one end and having an optical element mounted in and closing the other end thereof, means to mount said cylinder in the other end of said Dewar flask with said open end of said cylinder extending into the interior of said Dewar flask, the interior of said Dewar flask between the adjacent ends of said rod and said cylinder forming a chamber, and a layer of absorbent material in the inside of said cylinder, said material being adapted to serve as a source of volatile vapor for providing a supersaturated vapor in said chamber, the walls of said Dewar flask, at least adjacent said chamber, being transparent to afford a path for external light to pass through said chamber whereby cloud trails created when ionizing particles pass through said chamber may be viewed through said optical element.
4. A diffusion cloud chamber, comprising a cylindrical Dewar flask open at both ends, an insulated container open at one end and adapted to contain a freezing mixture, a metallic heat conductive rod, mounting means for supporting said rod at an intermediate portion thereof in one end of said Dewar flask, stopper means for closing said open end of said container and for supporting said one end of said Dewar flask in said open end of said container whereby one end of said rod extends into said container to provide substantial heat transfer contact between said rod and said freezing mixture, the other end of said rod extending into the interior of said Dewar flask, a hollow cylinder open at one end and having an optical element mounted in and closing the other end thereof, means to mount said cylinder in the other end of said Dewar flask with said open end of said cylinder extending into the interior of said Dewar flask, the interior of said Dewar flask between the adjacent ends of said rod and said cylinder forming a chamber, and a layer of absorbent material in the inside of said cylinder, said material being adapted to serve as a source of volatile vapor for providing a supersaturated vapor in said chamber, vaporization of said volatile vapor occurring through heat transfer between said material and atmospheric air external of said cylinder, the walls of said Dewar flask, at least adjacent said chamber, being transparent to afford a path for external light to pass through said chamber whereby cloud trails created when ionizing particles pass through said chamber may be viewed through said optical element.
5. A diffusion cloud chamber, comprising a cylindrical Dewar flask open at both ends, an insulated container open at one end and adapted to contain a freezing mixture, a metallic heat conductive rod, mounting means for supporting said rod at an intermediate portion thereof in one end of said Dewar flask, stopper means for closing said open end of said container and for supporting said one end of said Dewar flask in said open end of said container whereby one end of said rod extends into said container to provide substantial heat transfer contact between said rod and said freezing mixture, the other end

of said rod extending into the interior of said Dewar flask, a hollow cylinder open at one end and having an optical element mounted in and closing the other end thereof, means to mount said cylinder in the other end of said Dewar flask with said open end of said cylinder extending into the interior of said Dewar flask, the interior of said Dewar flask between the adjacent ends of said rod and said cylinder forming a first chamber, said other end of said rod having an opening forming a second chamber communicating with said first chamber and in line of sight with said optical element, said second chamber having a black lining, and a layer of absorbent material in the inside of said cylinder, said material being adapted to serve as a source of volatile vapor for providing a supersaturated vapor in said first chamber, the walls of said Dewar flask, at least adjacent said first chamber, being transparent to afford a path for external light to pass through said first chamber whereby cloud trails created when ionizing particles pass through said first chamber may be viewed through said optical element.

6. A diffusion cloud chamber, comprising a cylindrical Dewar flask open at both ends, an insulated container open at one end and adapted to contain a freezing mixture, a metallic heat conductive rod, mounting means comprising a washer for supporting said rod at an intermediate portion thereof in one end of said Dewar flask, stopper means for closing said open end of said container and arranged to cooperate with said washer for supporting said one end of said Dewar flask in said open end of said container whereby one end of said rod extends into said container to a point adjacent the bottom of said container, the other end of said rod extending into the interior of said Dewar flask, a hollow cylinder open at one end and having an optical element mounted in and closing the other end thereof, means to mount said cylinder in the other end of said Dewar flask with said open end of said cylinder extending into the interior of said Dewar flask, the interior of said Dewar flask between the adjacent ends of said rod and said cylinder forming a first chamber, said other end of said rod having an opening forming a second cylindrical chamber in communication with said first chamber, said second chamber having a diameter substantially equal to the diameter of said cylinder and being in axial alignment therewith, said second chamber having a black lining, and a layer of absorbent material disposed inside of said cylinder, said material being adapted to serve as a source of volatile vapor for providing a supersaturated vapor in said first chamber, the walls of said Dewar flask, at least adjacent said first chamber, being transparent to afford a path for external light to pass through said chamber whereby cloud trails created when ionizing particles pass through said first chamber may be viewed through said optical element.

7. A diffusion cloud chamber, comprising a cylindrical Dewar flask open at both ends, an insulated container open at one end and adapted to contain a freezing mixture, a metallic heat conductive rod, mounting means for supporting said rod at an intermediate portion thereof in one end of said Dewar flask, stopper means for closing said open end of said container and for supporting said one end of said Dewar flask in said open end of said container whereby one end of said rod extends into said container, the other end of said rod extending into the interior of said Dewar flask, a hollow metal cylinder open at one end and having an optical element mounted in and closing the other end thereof, said cylinder having external threads adjacent said one end thereof, means to mount said cylinder in the other end of said Dewar flask with said open end of said cylinder extending into the interior of said Dewar flask, said last mentioned means comprising a bushing having internal threads in threaded engagement with said external threads, the interior of said Dewar flask between the adjacent ends of said rod and

said cylinder forming a first chamber, said other end of said rod having an opening forming a second cylindrical chamber in communication with said first chamber, said second chamber having a diameter substantially equal to the diameter of said cylinder and being in axial alignment therewith, said second chamber having a black lining, and a layer of absorbent material in the inside of said cylinder, said material being adapted to serve as a source of volatile vapor for providing a supersaturated vapor in said first chamber, the walls of said Dewar flask, at least adjacent said first chamber, being transparent to afford a path for external light to pass through said first chamber whereby cloud trails created when ionizing particles pass through said first chamber may be viewed through said optical element.

8. A diffusion cloud chamber, comprising a cylindrical Dewar flask open at both ends, a vacuum insulating container open at one end and adapted to contain a freezing mixture, a metallic heat conductive rod, mounting means comprising a washer for supporting said rod at an intermediate portion thereof in one end of said Dewar flask, stopper means for closing said open end of said container and arranged to cooperate with said washer for supporting said one end of said Dewar flask in said open end of said container whereby one end of said rod extends into said container, the other end of said rod extending into the interior of said Dewar flask, a highly heat conducting hollow metal cylinder open at one end and having an optical element mounted in and closing the other end thereof, said cylinder having external threads adjacent said one end thereof, means to mount said cylinder in the other end of said Dewar flask with said open end of said cylinder extending into the interior of said Dewar flask, said last mentioned means comprising a bushing in fixed sealing engagement with said other end of said Dewar flask and having internal threads in threaded engagement with said external threads, the interior of said Dewar flask between the adjacent ends of said rod and said cylinder forming a first chamber, said other end of said rod having an opening forming a second cylindrical chamber in communication with said first chamber, said second chamber having a diameter substantially equal to the diameter of said cylinder and being in axial alignment therewith, said second chamber having a black lining, and a layer of absorbent material in the inside of said cylinder, said material being adapted to serve as a source of volatile vapor for providing a supersaturated vapor in said first chamber, the walls of said Dewar flask, at least adjacent said first chamber, being transparent to afford a path for external light to pass through said first chamber whereby cloud trails created when ionizing particles pass through said first chamber may be viewed through said optical element.

9. A diffusion cloud chamber as set forth in claim 8 in which said cylinder has an opening in the wall thereof, and removable means for closing said opening.

10. A diffusion cloud chamber as set forth in claim 3 in which means are provided to create a high potential difference between said rod and said cylinder.

11. A diffusion cloud chamber as set forth in claim 8 in which said black lining is made from a black paper cylinder having an open end facing said first chamber and having a black paper end.

12. A diffusion cloud chamber as set forth in claim 8 in which said absorbent material is filter paper.
